UNITED STATES PATENT OFFICE.

DANIEL G. SAUNDERS, JR., OF KANSAS CITY, MISSOURI.

METHOD OF AND APPARATUS FOR DEFENSE.

1,238,827.

Specification of Letters Patent.

Patented Sept. 4, 1917.

Application filed March 22, 1916. Serial No. 85,834.

To all whom it may concern:

Be it known that I, DANIEL G. SAUNDERS, Jr., a citizen of the United States, residing at Kansas City, in the county of Jackson 5 and State of Missouri, have invented certain new and useful Improvements in Methods of and Apparatus for Defense; and I do declare the following to be a full, clear, and exact description of the invention, such as 10 will enable others skilled in the art to which it appertains to make and use the same, reference being had to the accompanying drawings, and to the letters and figures of reference marked thereon, which form a part 15 of this specification.

My invention relates to a method of, and apparatus for positioning heavy guns, and has for its principal object to transport and set heavy long range guns at strategic points 20 to afford protection or defense for a long coast line, or border with a minimum number of guns.

The long range guns used in modern warfare are necessarily of such great weight 25 that it is impractical to move them with ordinary transportation facilities, so that when they are once positioned, they constitute a permanent defense for that point, but are unavailable for other localities, so that an 30 enemy might attack from a point out of range of the permanently mounted gun and thereby render the gun ineffectual or powerless from a defensive standpoint.

As guns of long range are of very expensive manufacture, it would constitute a considerable drain on any government to locate guns at all points where they might be needed and where they should necessarily be positioned to repel an enemy along an entire 40 coast line or border.

I have, therefore, in the present invention, provided for defending a long coast line, or border with a number of large or long range guns which ordinarily would be totally insufficient, by providing for the transfer of the guns from point to point, and by providing suitable foundations for the guns at strategic points or where they might be required.

In carrying out the invention, I locate permanent foundations at the strategic points and connect these foundations by tracks over which trucks upon which the guns may be carried are run, the tracks extending into the

foundations so that trucks carrying the guns may be run onto the foundations and the guns removed from the trucks and placed on the foundations and again removed from the foundation and placed on the trucks when they are to be moved to different points.

In carrying out the invention, I have provided improved details of structure, the preferred forms of which are illustrated in the accompanying drawing, wherein:

Fig. I is a perspective view of a defense system comprising my improvements.

Fig. II is a perspective view of a gun foundation and part of a connecting track, illustrating the connection of the track with the foundation and showing a long range gun on a truck that is being moved over the track.

Fig. III is a perspective view of the gun as it appears on the foundation.

Fig. IV is a perspective view of a modified form of gun carriage and foundation.

Referring more in detail to the drawings:

1 designates a solid foundation, preferably composed of concrete and having a sunken, circular bed 2, within which a platform 3 is rotatably mounted, the said platform being preferably supported upon roller or like bearings 4, so that it may be turned in order that a gun carried thereby may be aimed in different directions.

Sunk in the platform 3, so as to avoid projection therefrom are truck rails 5, and sunk in the foundation 1 and adapted for co-operation with the rails 5, are other sections of track rails 6, which in turn are adapted for co-operation with the rails 7 of an ordinary railway track 8, which leads to the foundation, and over which a truck 9, that is adapted for carrying a heavy load is adapted to travel.

10 designates a gun of any suitable type, here shown to be of long range, and which is mounted in any suitable manner on the carriage 11, the construction of the gun and carriage forming no part of my present invention, as the invention is adapted for application to guns of any heavy type.

The gun carriage 11 is of greater width than the truck 9, so that its side edges project beyond the edges of the truck, in order that suitable jacks may be applied to the carriage to lift it from the truck

and let it onto the platform 3 when the truck is moved onto the platform, or vice versa.

The jacks are here shown mounted on the gun carriage 11 and comprise the screws 12 that work in barrels 13 formed integrally with the gun carriage and provided with wheels 14, whereby the jack screws may be manipulated. The gun carriage is also provided, at its longitudinal edges, with apertures 15 which are adapted for receiving bosses 16 on the platform 3 when the gun carriage is let down onto the platform to anchor the carriage to the platform and to prevent its displacement following discharge.

In Fig. IV I have illustrated a modification of the platform and gun carriage construction, wherein the platform contains a bed 17 similar to the bed 2 in the foundation 1 and within which a platform 18 is adapted to turn. In the modified form, however, the platform also constitutes the gun carriage as the gun 19 is mounted permanently thereon. In this modification the flat foundation is provided with an entrance way 20 through which the truck 9, with the gun mounted thereon, may enter the bed.

The platform 18 is also provided with suitable jacks, indicated by the barrels 21, although I prefer in some instances to locate the jacks in the foundation, or independently of both the foundation and carriage, but which are adapted to be raised and lowered to raise and lower the gun carriage.

In utilizing the invention, I locate the foundations at suitable points along a coast line, a border or other defensive line and at suitable intervals to afford satisfactory defense when the guns of a desired caliber are mounted thereon. I then connect all of the foundations by a railway track, having branches adapted for coöperation with the foundation tracks to carry trucks onto the foundation platforms, and provide gun carriages of a construction that will coöperate with the receiving platforms of the several foundations to anchor the guns to the platforms in a manner that will afford satisfactory use of the guns.

With the foundations connected in this way, a limited number of guns may be provided, as when the guns are needed at any particular points, they may be loaded onto trucks and carried to such points.

When a gun reaches a foundation on a truck 9, the truck is run onto the foundation platform, and the jacks operated to lift the gun carriage from the truck so that the truck may be run from beneath the carriage. The jacks are then operated in the reverse direction to let the carriage down onto the platform, so that the anchoring members on the platform and carriage will coincide to anchor the carriage securely to the platform.

The platform may then be turned about, in order that the gun may be properly aimed and the gun used in the usual manner. After the gun has performed its offices at one point, it may remain at that point, or if it is required elsewhere, it may again be mounted on the truck and run to the point where its use is desired.

It is apparent that with a coast, or border line equipped with the foundations so described and connected by the railway track, guns of heavy caliber may be transported from point to point, so that the coast, or border line may be effectually protected without the necessity for the vast investment in guns that would be required if permanently mounted guns were located at sufficiently close intervals along the coast or border line to afford the protection that can be given under the present method.

Having thus described my invention, what I claim as new therein, and desire to secure by Letters-Patent, is:—

1. In an apparatus of the class described, a foundation comprising an element for revolvably supporting a gun carriage, a railway track on the foundation, a railway track leading to and coöoperative with the foundation track, a truck movable over said tracks, a gun carriage separate from and adapted for transport on the truck, and means for lifting the gun carriage from the truck to permit removal of the truck and lowering of the carriage onto the foundation.

2. In an apparatus of the class described, a foundation comprising an element for revolvably supporting a gun carriage, a railway track on the foundation, a railway track leading to and coöoperative with the foundation track, a truck movable over said tracks, a gun carriage separate from and adapted for transport on the truck, means for lifting the gun carriage from the truck to permit removal of the truck and lowering of the carriage onto the foundation, and ground means coöoperative with the lifting means to center the gun carriage relative to the foundation when the carriage is lowered thereonto.

3. The combination with a foundation, having a platform bed downset therein and having a trackway opening through one edge into the bed, a gun platform adapted for rotation in said bed, tracks at the bottom of said bed and extending through said trackway, and a track leading to the track in the foundation trackway.

4. The combination with a foundation, of a platform rotatably mounted in the foundation, tracks on the foundation and platform adapted for coextension, a track leading to the foundation track, a gun carriage, trucks supporting said gun carriage and adapted for travel over said tracks, and jacks for

raising the carriage from and lowering the same onto the platform and trucks.

5. The combination with a foundation, having a circular bed, of a platform rotatably mounted in said bed, tracks sunk in the foundation and platform and adapted for coextension, a track leading to the foundation tracks, trucks movable over the said

tracks, a gun carriage adapted for removable support on said trucks, and jacks on the carriage for raising the gun carriage from said trucks and lowering the same onto said platform.

In testimony whereof I affix my signature.

DANIEL G. SAUNDERS, JR.
